COMBINED DRAWER FRONT AND CABINET DOOR PANEL

Howard E. Patron, West Islip, N.Y., assignor to
Homecraft Products, Inc., Brooklyn, N.Y.

Filed Nov. 8, 1971, Ser. No. 196,878

Term of patent 14 years

Int. Cl. D6—06

U.S. Cl. D6—192

FIG. 1 is a front elevational view of a combined drawer front and cabinet door panel showing my new design;

FIG. 2 is a right side elevational view;

FIG. 3 is a left side elevational view;

FIG. 4 is a top plan view, the bottom plan view being a mirror image thereof;

FIG. 5 is a rear elevational view at greatly reduced scale;

FIG. 6 is a sectional view taken along line 6—6 of FIG. 1 on an enlarged scale; and

FIG. 7 is a sectional view on the same scale as FIG. 6, taken along line 7—7 of FIG. 1.

I claim:

The ornamental design for a combined drawer front and cabinet door panel, substantially as shown and described.
